PUMP

William H. Hazard, Chicago, Ill., assignor to
 Woodruff & Edwards, Inc., Elgin, Ill., a corpora-
 ration of Delaware

Application July 3, 1944, Serial No. 543,326

9 Claims. (Cl. 103—148)

1

This invention relates to fluid pumps, and more particularly to a pump having bellows elements to produce suction and compression for movement of the fluid therethrough.

More specifically, the invention has reference to a pump having a plurality of bellows pumping elements operating alternately to reduce the number of pulsations in the fluid flow.

While pumps of the bellows type per se are known, it is recognized that a single bellows will produce a defined pulsating flow not to be desired. One of the principal objects of my invention is to provide a pump using a plurality of bellows elements operating alternately to provide a flow that is substantially continuous, i. e., devoid of the undesirable interrupted flow inherent in single-acting pumps.

It is necessary in most pumps now available to recondition the valves from time to time by refacing the seats and valves or to replace either or both. Frequently this is a serious problem, as the valves are so arranged that a major portion of the pump must be disassembled for access thereto, and the valves are so built into the unit so that replacement of the valve mechanism as such cannot readily be made.

Accordingly, other objects are to provide a pump as above referred to, having its valves assembled as a unit, which may, when worn beyond efficient functioning, be quickly removed from the pump proper and easily replaced with another unit; and further, to provide valve seats of material of relative softness in order that they may, when worn, be removed without injury to other parts of the pump. In this manner the pump is out of service for a negligible period and repairs may be made with the least trouble and expense. Moreover, in the present invention the valve assembly is in no way associated with the suction and discharge piping, and therefore these need not be disturbed for servicing of the valves.

Under certain conditions of installation it is desirable to mount the pump so that the belt drive from the motor to the pump proper is easily accessible for replacement of the exhaustible belts or for attention to the bearings. With pumps presently available the suction and discharge openings are in specified locations so that to position the pump for best accessibility of the parts mentioned is not always convenient as the pipe connections are fixed on the pump and a crossed routing of the piping to accommodate the same to the position of the pump is not always feasible.

Accordingly, a further object is the provision of a pump having a reversible driving assembly

2

so that it may, before installation, be interchanged as a unit from one side of the pump to the other; and furthermore to provide a valve unit assembly which may be rotated from one mounted position to another to locate the suction and discharge valves on their respective sides of the pump to suit the inlet and outlet pipes.

In pumps having a piston closely fitting within a cylinder, as well as those having rotary fluid displacing elements, the problems of wear due to inertia and unbalance of the moving parts, replacement of piston rings, leathers and various forms of packing are conductive to expensive maintenance. Furthermore, in those mechanisms the lubricating oil and grease may readily mix with the fluid being pumped.

In the pump of the present invention, a further aim is to eliminate any possibility of mixing of the lubricating oil and grease with the fluid passing therethrough by effectively isolating the lubricant from the fluid chambers, and, by the use of bellows elements for the pumping action, reducing the problems of wear and maintenance to a negligible degree. Moreover, a substantial reduction in friction losses is attained and water leakage entirely eliminated. In pumps utilizing valve discs of fibre or rubber compounds it is desirable to prevent them from drying out as this often results in cracking of the material. Therefore, an additional advantage resides in the arrangement of the several chambers of the present pump in their relation to the valves, so that the latter are at all times immersed in fluid.

The pump to be described is intended primarily for operation on farms or for other uses where an expert maintenance mechanic is not ordinarily available. Thus a simple, effective, trouble-free unit is the prime consideration. Such advantages inherent in the subject invention will appear as the description proceeds.

Now referring to the drawings:

Figure 1 is a side elevational view with certain portions broken away for clarity;

Fig. 2 is an end elevational view looking toward the motor, and also having certain parts broken away;

Fig. 3 is a cross-sectional view on the line 3—3 of Fig. 1 with certain parts broken away and with the bellows pumping element there shown in expanded position; and

Fig. 4 is a cross-sectional view on the line 4—4 of Fig. 3, and with certain parts broken away.

Directing attention now to Figure 1, the base 11 is substantially a box-like structure provided with a pair of legs 12, which are desirably bolted

to the floor, and are reinforced by a rib 13 extending therebetween. Surmounting the legs is the chamber 14 closed on all sides and the bottom except for a rectangular aperture 15 in the top thereof.

Extending from one side of the base 11 is the ear 21 bearing a pivot 22 on which is journalled the bifurcated extension 23 carried on the motor shelf 24. The shelf 24 is provided with a downwardly extending arm 25 having a hole 26 adapted to fit over the threaded stud 27 fixed in the wall of the base 11. A washer 31 and nut 32 serve to retain the arm 25 on the stud 27 against the thrust of the coil spring 33. By the means just described the motor shelf 24 may be tilted clockwise or counterclockwise to increase or diminish the tension of the drive belt, the nut 32 serving to adjust the desired tension. It is to be noted that the pivot 22 is displaced from the vertical center line of the motor 35. Thus the weight of the motor, motor shelf, and their associated parts always tends toward clockwise rotation about the pivot 22 and provides constant regulation of the tension in the belt 42.

Carried on the motor shelf 24 by bolts 34 is the electric motor 35 bearing on its shaft the grooved pulley 41. In certain locations it may be desirable to substitute a gasoline motor or other prime mover for the electric motor. The motor 35 drives, through the V-belt 42, the flywheel 43, which may be grooved or provided with a flat or crowned face, as preferred. The flywheel 43 is keyed or fastened in any common manner (Fig. 2) to the main shaft 51, the latter being journalled in ball or roller bearings 52 fitted with the housing 53. A shoulder 54 bears against an oil seal 61 of any well-known type to eliminate leakage of lubricant around the shaft 51. The housing 53 is provided with a peripheral flange 62 having a plurality of holes 63 through which pass the cap screws 64 securing the housing to the base 11. Intermediate the shaft 51 and housing 53 is the oil chamber 65 communicating with the chamber 14 by means of conduit 66 terminating in a cup 67. Return of lubricant from the chamber 65 to the chamber 14 is provided through the inner one of bearings 52 and through the outer bearing 52 and conduit 68.

The flange 62 is provided with a finished inner face 71 adapted to contact a correspondingly shaped outer finished boss 72 on the base 11. A finished inwardly extended portion 73 is fitted into a finished corresponding aperture 74 in the base 11. By reason of the engaging surfaces 71 and 72 and 73 and 74 the main shaft assembly as carried by housing 53 is maintained in a predetermined accurate position in all three directions.

Directly opposite the aperture 74 in the other wall of the base 11 is an identical aperture 81 normally covered by a plate 82 held to the base 11 by cap screws 83 and provided with a hole 84 stoppered by a plug 85 whereby oil may be poured into the bottom of the chamber 14 and maintained at the level fixed by the elevation of the top of the opening 84. Another opening 86 in the base 11 (Fig. 1) closed by a plug 87 serves to drain lubricant from the chamber 14.

Should it be desired to locate the drive assembly shown at the left in Figure 2 on the right-hand side, only the belt 42 and screws 64 need be removed and the entire drive assembly relocated on the other side. In that case plate 82 and its associated parts are substituted on the left-hand side over the aperture 74. The electric motor 35 or other prime mover may be correspondingly reversed by means of bolts 34.

Fixed to the inner extremity of the drive shaft 51 by a pin 91 is the collar 92 bearing an eccentrically located cylindrical post 93. Rotatably mounted by one end thereof on the post 93 is the connecting rod 95 (Fig. 1). An anti-friction bushing 96 is shown interposed between the post 93 and connecting rod 95. Extending radially from the collar 92 is an arm 97 provided with a fixed blade or paddle 98 for a purpose to be described.

The opposite extremity of the rod 95 is journalled on a pivot 101 also provided with an anti-friction bushing 102, the pivot 101 being carried by the bifurcated arm 103 of the bell crank 104. Only sufficient clearance is left between arm 103 and rod 95 to permit freedom of movement of the latter while maintaining the rod 95 in its desired lateral position so that removal of the drive shaft assembly may be effected without removing the connecting rod from its associated mechanism. The bell crank 104 rocks on the pivot 105 supported in the bifurcated bracket 106 fastened to an intermediate casing 111 by screws 106a.

The intermediate casing 111 is substantially rectangular in form and is provided with a rim 112 co-extensive with the border of the aperture 15 and sealed with respect to the casing 111 by a gasket 113. Casing 111 is partitioned medially by a wall 121 to provide two independent chambers 122 and 123 for reception of the bellows elements 124 and 125.

Bellows 124 and 125 are of resilient metal and of a type comprising a number of diaphragms soldered together at their peripheries to form sections of which there may be one or more. To the topmost flange of each bellows is fastened an end fitting 131 having an inwardly extending connection 132 provided with a screw-threaded hole 133. Engaging said hole 133 is a drive rod 134 held in proper relation to the connection 132 by a lock-nut 135.

To the lowermost flange of each bellows is attached an end fitting 141 and integral therewith is the sleeve 142 externally threaded at its lower end as at 143 and received in a hole 144 in the floor 145 of the casing 111. A gasket 151 is provided between disc 141 and the floor 145 and the sleeve 142 locked into position by the nut 152.

Drive rod 134 extends through the sleeve 142 and is provided at its lower end with threads engaging a correspondingly threaded hole 153 in the head 154. A lock nut 155 maintains the proper relative position of the head 154 and rod 134. Each head 154 is journalled on a pivot 161 carried on an arm 162 of the bell crank 104. Each arm is provided with a pocket 163 in fluid connection with the pivots 161 through oil holes 164 into which a wick may be inserted.

During operation, the motion of the paddle 98, the connecting rod 95 and the bell crank 104 create a splash in the well of oil in the bottom of the chamber 14. Hence, the oil is effectively circulated to the bearings 52, 96, 102, 105, and 161, and oil also reaches the rods 134. However, since any such oil that may go beyond the floor 145 is effectively retained within the bellows no opportunity exists for admixture of oil with the fluid being pumped.

The casing 111 (Fig. 3) also includes an inlet port 171 threaded for reception of a standard pipe, and connected with a passage 172 adjacent chambers 122 and 123 but separated therefrom by a partition 173. An opening 174 at the top of the passage 172 is provided for a purpose to be described.

At the opposite side of the pump there is a threaded outlet port 175 connected with another passage 176 also adjacent chambers 122 and 123 but separated therefrom by a partition 177. An opening 178 corresponding to opening 174 is also provided.

Mounted directly above the casing 111 is the substantially flat valve plate 181 (Figs. 1 and 3) coextensive with casing 111, and separated therefrom by a gasket 182. The plate 181 is pierced by four circular openings 183, a pair being associated with each bellows chamber 122 and 123 and the members of each pair being distributed on either side of each bellows element 124 and 125 (Fig. 4). Each opening 183 is occupied by a valve seat 184 pressed thereinto and secured further by being peened over as at 185 into the chamfered rim of the opening 183. The seat 184 is provided with a peripheral flange 186 to engage the face of the plate 181 and thereby locate the seat accurately with respect thereto. Preferably the valve seats 184 are formed from relatively soft metal so that, for replacement, it is a simple matter to remove them by chiseling, press in a new seat and peen the edge as aforesaid, without the danger of cracking the valve plate 181.

Extending radially inward from the wall of the seat 184 is the pair of arms 191 (Fig. 4) supporting a central boss 192 provided with a circular aperture 193. Thus the arms 191 define a pair of reniform ports 194 for the passage of fluid through the seat 184.

Fitted within the aperture 193 and rigidly secured with respect to the seat 184, as by peening, is the cylindrical post 195. Adapted to slide axially on said post 195, normally covering the ports 194 and substantially coextensive with the seat 184, is the circular valve disc 201. A conical coil spring 202 capped by a bushing 203 normally urges the disc 201 into closing relation with the ports 194. A cotter or like pin 204 passing through the post 195 serves to prevent bushing 203 from being forced away from the spring 202.

Carried above the plate 181 and sealed thereto by the medium of a gasket 211 is the upper casing 212, subdivided by a partition 213 at right angles to partition 121 to form the inlet chamber 214 and outlet chamber 215. The upper casing 212 is further partially subdivided by partitions 216 and 217 to form with the horizontal offset roof of the casing 212 the inlet port 218 and outlet port 219 respectively, and those walls 216 and 217 continue in right-angled branches 221 and 222 toward the center partition 213 to form together with the walls of the casing 212 reservoirs 223, 224, 225 and 226, whereby the valves are always submerged and hence primed for prompt pumping upon starting of the pump. The uppermost chamber portions 231 and 232 of the casing 212 serve as air and vacuum chambers to cushion the pulsations of the pump and thereby result in a smooth flow of fluid therethrough. It will be noted that partitions 216 and 217 form with the outer walls of the casing 212, the channels 233 and 234.

To maintain the casing 212, the valve plate 181, the intermediate casing 111 and their gaskets in fixed relation with each other, there is provided a plurality of bolts 241, in this case, four in number, passing through ears 240, 242 and 243 forming integral parts of the chambers 212, plate 181 and casing 111, respectively. The casing 111 is attached to the base 11 by means of bolts 255 passing through the floor of the casing 70

111 and ears 257 integral with the base 11. Washers 256 of rubber or the like serve to seal the openings through which the bolts 255 pass.

Advertising particularly to Figure 2, the chamber 212 is provided with priming ports 251 and 252 closable by plugs 253 and 254, individual to the chambers 214 and 215, and for the usual purpose, when necessary, of admitting fluid to the chambers for priming the pump upon starting.

Having described the construction of the invention, its operation will now be detailed. Assuming the pump is dry from having been inactive, it is first primed as noted in the foregoing paragraph, and the motor or engine started by a suitable switch or other suitable means (not shown). Through the belt 42 the shaft 51 is rotated to operate the eccentric 93, the associated connecting rod 95 and bell crank 104, and thereby impart alternated reciprocating motion to the rods 134, one individual to each bellows 124 and 125. Inasmuch as the action of both bellows is identical but alternated, the operation of only one, 124, will be described, and from that mode of operation the action will be seen to be analogous to the displacement of fluid by a piston within a cylinder.

As the bellows 124 is compressed by a downward movement of the arm 162 appurtenant thereto, its volume is decreased and a suction created within the chamber 122. The inlet valve 201 associated with the chamber 122 thereupon opens and fluid enters the chamber from inlet 171, chamber 172, opening 174, channel 233, port 218, chamber 223, and ports 194, the discharge valve 201 (at the left in Fig. 3) meanwhile remaining closed due to the suction.

Upon upward movement of the rod 134 the bellows 124 is expanded, thereby increasing its volume and producing a pressure in the chamber 122. Thereupon inlet valve 201 is permitted to close under urging of its spring 202 and discharge valve 201 is opened to permit the fluid to be discharged through the valve, the chamber 224, port 219, channel 234, opening 178, chamber 176 and out through the discharge port 175.

It will be observed that as bellows 124 is acting for suction, bellows 125 is acting for discharge and vice versa, each operating independently through its individual pair of suction and discharge valves 201, but through common inlet and discharge passages. In this way the pressure and suction waves in the fluid overlap to produce a substantially even flow, i. e., the ripple ordinarily present in the flow of a single acting pump is flattened to a substantial extent.

From the foregoing it will be noted that the valve plate assembly is a simple unit and that all four individual valve assemblies are identical in construction, regardless of whether the valve is used on the suction or discharge side of the pump. Furthermore, the valve assemblies and the valve mounting plate 181 constitute a unit severable from the remainder of the pump without the need of disconnecting any moving parts or pipe connections. Thus, in the event of replacement or repair of a valve element, the entire plate and valves are dissociated from the pump and replaced as an entity, thereby avoiding the problems that would arise by improper refacing or repair of a valve by an inexperienced person. However, it will be appreciated that if desired any particular valve may be quickly disassembled for servicing by removing the pin 204.

Moreover due to the symmetrical nature of the 75 valve plate and its assembled parts the entire

valve unit may be rotated horizontally to suit the location of the inlet and outlet pipes, i. e., assuming a particular position of inlet and outlet pipes, only the valve plate need be turned and the pump reverses its action. In connection with such modification no other parts of the pump except the bolts 241 need be disturbed.

One of the principal advantages of the present invention resides in the use of a bellows element as the fluid-displacing means. From the construction described it will be seen that the fluid being pumped is completely isolated from the lubricant used on the other moving parts. Thus, the pump is ideally adapted to the movement of fluids which must be carefully guarded against contamination, e. g., drinking water, milk and chemicals. The bellows itself is self-lubricating in that the surrounding fluid effectively disposes of the heat generated by molecular friction within the metal of the bellows.

A particular advantage of the pump of my invention resides in the elimination of packing as used in the conventional type of reciprocating pump in which a piston operating within a cylinder is used as the fluid displacing means. In that type the piston rod ordinarily associated with the piston must be sealed by the use of a stuffing box and gland and when naphtha, gasoline and similar petroleum products are pumped it is found that the packing which must be employed in the stuffing box is subject to rapid deterioration by these products. In the present apparatus no packing is employed and with obvious advantages.

Another important consideration is the absence of any free passage from the pumping chambers. Hence, once primed, the pump chambers are always filled with fluid, and the pump is always prepared for instant action. Furthermore, due to the partitions 216, 217, 221 and 222, the valves are always immersed and hence primed.

As compared to the commoner types of pumps using a reciprocating piston within a cylinder, or rotary fluid displacing elements in which wear is a serious impediment, it is interesting to note that the bellows described and shown herein has, on test, been expanded and compressed 600,000,000 times without failure, and since that indicated an indefinite life, the test was abandoned.

It will be understood that the invention is not limited to a pump provided with two chambers, each enclosing a bellows, but that there may be a plurality greater than two. In such event the main drive shaft would comprise a crank shaft having the desired number of cranks, each having its connecting rod actuating a pair of bellows through a bell crank as shown, or its equivalent.

Without further elaboration, the foregoing will so fully explain the gist of my invention that others may, by applying current knowledge, readily adapt the same for use under varying conditions of service, without eliminating certain features, which may properly be said to constitute the essential items of novelty involved, which items are intended to be defined and secured to me by the following claims.

I claim:

1. A fluid pump, comprising in combination, a plurality of pumping chambers, a plurality of sectional bellows of resilient metal, one individual to each said pumping chamber within the same and fixed at one end to a wall thereof, a base, a common inlet chamber, a common outlet

chamber, both said chambers common to said pumping chambers, a plurality of inlet valves, one individual to each pumping chamber and serving to interconnect its said pumping chamber to said inlet chamber, a plurality of outlet valves, one individual to each pumping chamber and serving to interconnect its said pumping chamber to said outlet chamber; and means to compress and expand each said bellows successively and repeatedly to introduce fluid from said common inlet chamber to its said pumping chamber through its associated inlet valve, and to discharge said fluid from its said pumping chamber through its associated outlet valve to said common outlet chamber, said means comprising a housing supported on said base and including bearings, a crank shaft carried on said bearings, power-driven means to rotate said crank shaft, a plurality of rods, one individual

10 to each said bellows and connected to the free end of each said bellows, means for operatively connecting said crank shaft to said rods to subject each said bellows to reciprocatory alternate compression and expansion, said housing being 15 to said common outlet chamber, said means comprising a housing supported on said base and including bearings, a crank shaft carried on said bearings, power-driven means to rotate said crank shaft, a plurality of rods, one individual to each said bellows and connected to the free end of each said bellows, means for operatively connecting said crank shaft to said rods to subject each said bellows to reciprocatory alternate compression and expansion, said housing being 20 adapted to be supported on said base at either side thereof selectively.

2. A fluid pump, comprising in combination, an upper chamber subdivided into inlet and outlet compartments; a lower chamber subdivided into a plurality of pumping compartments, each said pumping compartment including a sectional bellows of resilient metal; a plurality of inlet valves and a plurality of outlet valves, one of each individual to each pumping compartment and operable to connect each pumping compartment to the said inlet chamber and to the said outlet chamber alternately; and means to compress and expand said bellows to displace fluid through each said pumping compartment alternately.

3. A fluid pump, comprising in combination, an upper chamber subdivided into inlet and outlet compartments; a lower chamber subdivided into a plurality of pumping compartments, each said pumping compartment including a fluid-displacing element comprising a sectional bellows of resilient metal; a mounting plate intermediate said upper chamber and lower chamber and having a plurality of inlet ports and a like plurality of outlet ports therein; spring-pressed valve discs normally closing said ports and carried on said plate, and means for maintaining said upper and lower chamber and said plate in fixed relation.

4. A fluid pump comprising in combination an upper chamber subdivided into inlet and outlet compartments, a lower chamber subdivided into a plurality of pumping compartments, a base member having a reservoir for storage of lubricant, a pumping element in each said pumping compartment comprising a sectional bellows of resilient metal closed at one end and having an aperture at the other end, a sleeve having a flange at one end and an aperture through said sleeve, said sleeve passing through said first mentioned aperture to fix one end of said bellows to said pumping compartment, a rod connected to the free end of said bellows and extending into the base member, said rod fitting slidably within said second mentioned aperture whereby said sleeve forms a seal to minimize entry of lubricant to the interior of said bellows, and means for reciprocating said rod to compress and expand said bellows to displace fluid through said pumping compartments.

5. In a fluid pump, in combination, a plurality of fluid displacing elements; a base for said pump

having at least two parallel spaced sides; a pair of identical apertures in said sides, one individual to each said side; means intermediate said sides and connected to said elements to actuate the same to force fluid through the pump; a power-driven shaft to operate said means; a housing detachably secured to said base and including bearings to carry said shaft; said means including a crank pin driven by said shaft and a connection intermediate said elements and said pin, said connection being freely disengageable from said pin upon detachment of said housing from said base and means for mounting the housing and said shaft in either of said apertures interchangeably.

6. A fluid pump, comprising in combination, an upper chamber subdivided into inlet and outlet compartments, each said compartment determining a fluid zone and an air zone; a pumping chamber below said upper chamber and subdivided into a pair of pumping compartments; a pair of fluid displacing elements, one individual to each said pumping compartment and inclosed therein and comprising a sectional bellows of resilient metal; means for attaching one end of each said bellows to the floor of its individual pumping compartment and including a sleeve; a rod attached to the opposite free end of each bellows, said rod passing through said sleeve and guided thereby; a base for said pump; a three-armed lever pivoted on said base; means for operatively connecting each said rod to separate opposed arms of said lever; power-driven means including an eccentric; a link for operatively connecting said eccentric to the remaining arm of said lever; a valve mounting plate positioned between said upper chamber and said pumping chamber; a pair of inlet valves and a pair of outlet valves carried by said plate, a single member of each pair being individual to each pumping compartment; and means to maintain said upper chamber, said plate, said pumping chamber and said base in fixed relationship.

7. A fluid pump comprising in combination, a pumping chamber including a fluid displacing element, an inlet valve, an outlet valve, and a chamber disposed above said pumping chamber, said last mentioned chamber including partitions forming a pair of wells, one associated with each said valve and forming a fluid reservoir for submersion of said valves, and said last mentioned chamber including a dome forming an air-enclosing zone.

8. A fluid pump comprising in combination, a lower casing including partitions to form a pump-

ing chamber, an inlet chamber and an outlet chamber, said pumping chamber including a fluid-displacing element, and said inlet and outlet chambers each being provided with a port for intake of fluid to said pumping chamber and delivery thereof from said pumping chamber respectively, a valve plate provided with an inlet valve and an outlet valve, an upper casing defining a fluid chamber and an air-enclosing chamber, said plate being separably attached to and positioned intermediate said two casings.

9. A fluid pump comprising in combination, a lower casing including partitions to form a pumping chamber, an inlet chamber and an outlet chamber, said pumping chamber including a fluid-displacing element, and said inlet and outlet chambers each being provided with a port, one port providing an inlet to the pump and the other port providing an outlet from the pump, a valve plate provided with an inlet valve and an outlet valve, an upper casing defining a fluid chamber and an air-enclosing chamber, said plate being separably attached to and positioned intermediate said two casings, an inlet passage extending from the port associated with said inlet chamber through said plate to said fluid chamber, and an outlet passage extending from the port associated with said outlet chamber through said plate to said fluid chamber.
